(57) **CLAIM**

The ornamental design for an automatic injection device, as shown and described.

DESCRIPTION

FIG. 1 is a perspective view of the design with a top removable cap covering an activator button and a bottom removable cap covering an injection opening;

FIG. 2 is a front view of the design with the removable caps for the activator button and injection opening in covering positions;

FIG. 3 is a rear view of the design;

FIG. 4 is a right side view of the assembled design. The left side view is a mirror image of the right side, with the exception of the numbers “1” and “2”, which are not symmetric.

FIG. 5 is a top view of the design, illustrating the activator button;

FIG. 6 is a bottom view of the design; and,

FIG. 7 is a front view of the design with a top removable cap covering an activator button removed and a bottom removable cap covering an injection opening removed.

The broken line showing of parts of the drawings is included for the purpose of illustrating use and environment and forms no part of the claimed design.
